UNITED STATES PATENT OFFICE.

MICHAEL J. OSSMAN, OF LEADVILLE, COLORADO.

DEGREE-BEVEL-SCALE RULE.

1,248,897.

Specification of Letters Patent.

Patented Dec. 4, 1917.

Application filed April 25, 1917. Serial No. 164,483.

To all whom it may concern:

Be it known that I, MICHAEL J. OSSMAN, a citizen of the United States, residing at Leadville, in the county of Lake and State 5 of Colorado, have invented a new and useful Degree-Bevel-Scale Rule, of which the following is a specification.

The device forming the subject matter of this application is a folding rule, and one 10 object of the invention is to provide a rule of the kind above mentioned in which the graduations and various designating marks are so located that they will not be likely to be rubbed off or marred, after a protracted 15 period of use.

Another object of the invention is to provide a folding rule which may be used for laying off angles.

It is within the province of the disclosure 20 to improve generally and to enhance the utility of devices of that type to which the present invention appertains.

With the above and other objects in view which will appear as the description 25 proceeds, the invention resides in the combination and arrangement of parts and in the details of construction hereinafter described and claimed, it being understood that changes in the precise embodiment of the 30 invention herein disclosed can be made within the scope of what is claimed, without departing from the spirit of the invention.

In the accompanying drawings:—

Figure 1 shows in top plan, a rule constructed in accordance with the present invention, parts being broken away; and

Fig. 2 is a cross section on the line 2—2 of Fig. 1.

The rule forming the subject matter of 40 this application comprises parts 1, 2, 3 and 4, the parts 1 and 2 upon the one hand, and the parts 3 and 4, on the other hand, being united by hinges 5. The parts 1 and 3 are supplied at their outer ends with coacting 45 disks, the numeral 6 denoting the disk which is connected with the part 3. At 7 appears the pivot element whereby the disks are connected. The construction above described is the ordinary folding rule structure, and it 50 need not be set forth in greater detail, since

it is clearly understood by those skilled in the art.

In carrying out the present invention, the disk 6 is peripherally graduated, as shown at 8, the graduations 8 coöperating with the 55 inner edge of the part 1, to indicate the angle between the inner edges of the parts 1 and 3. The graduations 8 may be of any desired sort, and it will be seen readily that when the parts 1 and 3 are separated to define an angle, the value of the angle may be 60 read off on the graduations 8.

The parts 1, 2, 3 and 4 of the rule preferably are made of aluminum and have 65 graduations 9 of any desired sort. These 9 graduations 9 preferably are made by grooving the parts 1, 2, 3 and 4, as at 25, and filling the grooves with an enamel 26 which differs in color from the hue of the parts above specified.

On the ends of the parts 2 and 4 are placed caps 10 which preferably are made of steel, the caps being supplied with outwardly extended marking projections 11.

Each of the parts 1, 2, 3 and 4 of the rule 75 is supplied with a longitudinal recess 12, and is provided with a longitudinal rib 14 which outstands at the base of the recess and defines grooves 15 on each side of the rib. The outer face 16 of the rib is spaced 80 or set back from the outer face 17 of each part of the rule. Grooves or seats 18 are cut into the faces 16 of the rib 14, these seats being filled with enamel 19 and serve to form the numerals on the rule.

Because the other face 16 of the rib 14 is set back from the outer face 17 of the rule, the numerals formed in the seats 18 by the enamel 19 will not be marred when the rule is laid flat on an object. Further, since the 90 grooves 15 are provided on each side of the rim 14, dirt and the like finding its way into the recess 12 will be caught in the grooves 15 and will not accumulate on the outer faces 16 of the ribs 14 and obscure the numerals formed in the seats 18 by the enamel 19.

Having thus described the invention, what is claimed is:—

A rule having a superficial longitudinal recess and provided with a longitudinal rib 100

outstanding at the base of the recess and defining grooves on each side of the rib, the outer face of the rib being set back from the outer face of the rule, there being depressed character-forming seats in the outer face of the rib; and filling material in the seats.

In testimony that I claim the foregoing as

my own, I have hereto affixed my signature in the presence of two witnesses.

MICHAEL J. OSSMAN.
